G. HAKE,

GARMENT SUPPORTER.

APPLICATION FILED JUNE 25, 1917.

1,319,703.

Patented Oct. 28, 1919.

UNITED STATES PATENT OFFICE.

GEORGE HAKE, OF ST. LOUIS, MISSOURI.

GARMENT-SUPPORTER.

1,319,703.

Specification of Letters Patent. Patented Oct. 28, 1919.

Application filed June 25, 1917. Serial No. 176,766.

To all whom it may concern:

Be it known that I, GEORGE HAKE, a citizen of the United States of America, a resident of the city of St. Louis, State of Missouri, have invented certain new and useful Improvements in Garment-Supporters, of which the following is a full, clear, and exact description, reference being had to the accompanying drawings, forming a part 10 of this specification.

My invention relates to a garment supporter and has for its object the production of a simple, inexpensive and secure article of this kind so constructed as to avoid 15 possibility of the disconnection of a garment from the supporter, this object being attained by using a novel pressure member and an effective interlocking connection between a resilient clasp member and a clasp 20 keeper slidably fitted to said resilient clasp member.

Figure I is a front elevation of my garment supporter.

Fig. II is an enlarged front elevation of 25 the supporter, the clasp keeper being partly in section.

Fig. III is an elevation of the clasp, partly in section, the keeper being shown in raised position.

Fig. IV is a vertical section through the 30 supporter as it appears when in service with a garment attached thereto.

Fig. V is a cross section through the clasp.

Fig. VI is an end elevation of the roll or 35 button of my garment supporter.

In the drawings, A designates a suspension strap adapted to be secured to a supporting article of wearing apparel, for example, a corset, and B is a clasp carrier 40 attached to the suspension strap A by suitable means, such as a loop C.

The clasp carrier B includes two flexible or pliable straps, 1 and 2, parallel with each other. The strap 2 terminates in a roll 3 45 formed by winding the strap upon itself and preserving the roll thus formed by extending stitches thereinto, or in any other suitable manner. Said strap 2 is preferably of cloth and is therefore readily rolled to 50 produce the roll 3.

The strap 1 of the clasp carrier B has attached to it a keeper 4, preferably of metal. This keeper is provided with a slot 5 for the reception of a loop at the end of 55 the strap 1, and said keeper has end run-

ners 6 which engage the resilient member of the clasp of my garment supporter.

D designates the resilient clasp member of my garment supporter. This clasp member is of metal and is U-shaped in form, 60 comprising a bottom horizontal ledge element 7 and arms 8 extending upwardly from said ledge element. The arms 8 are provided with shoulders or detents 9 which receive the runners 6 of the keeper 4, said 65 runners being operable on said arms to seat beneath the shoulders 9 or to be disengaged from said shoulders and move upwardly along the arms.

In the practical use of my garment supporter, the garment to be attached to the supporter is secured to the clasp by placing a small portion of such garment in front of the roll 3 and passing said roll with the portion of the garment in front of it through 75 the resilient clasp member D, while the ledge element 7 and the keeper 4 are widely separated, as seen in Fig. III. At this time the runners 6 of the keeper are above the lower edges of the detent shoulders 9, and after 80 the roll 3 and the portion of the garment to be clasped have been passed through the member D as mentioned, said member D is elevated while the keeper 4 is held from upward movement therewith, and as a result 85 the runners 6 of the keeper become seated beneath the detent shoulders 9, as seen in Figs. I and II. When this has been done the roll 3 occupies the position seen in Fig. IV, with the engaged portion of the garment 90 extending almost completely around the roll and resting in part against the ledge element 7 of the resilient clasp member and partly against the keeper 4 above said ledge element. With the parts so connected, any pull exerted by the supporter and the garment in contrary directions tends to draw the roll 3 backwardly toward the space between the ledge element of the resilient clasp member and the keeper above 95 this ledge element, and inasmuch as this space is smaller than said roll the latter cannot pass therethrough but acts to bind the portion of the garment around it tightly against the opposing portions of the clasp, 100 thereby effectually preventing separation of the garment from the clasp of the garment supporter. When it is desired to detach the supporter from the garment it is only necessary to move the arms of the resilient 105

clasp member D toward each other to a sufficient degree to permit the runners 6 of the keeper 4 to be unseated from beneath the shoulders 9 on said arms, after which the resilient clasp member D is lowered to a sufficient extent to allow the roll 3 and the portion of the garment lying thereagainst to be drawn through the space between the ledge element 7 of the resilient clasp member and the keeper 4. The roll 3 of my garment supporter is of a special merit for the reason that it provides a very simple and inexpensive button or retaining device, comprising as it does merely a portion of the goods from which the strap 2 is formed, which may be readily produced by the simple expedient of a winding operation and the preservation of the roll thus formed. The roll 3 has the further point of merit that it may be of cloth or other soft material, which, when engaged by the gar-

ment to be held, will not cut, tear or otherwise injure the garment.

I claim:

A garment supporter comprising a pair of straps, one of which is provided with a button, a keeper attached to the other strap, and a U-shaped resilient clasp member having its arms slidably fitted to said keeper, said clasp member being movable independently of said strap and having a ledge element intermediate its arms toward which said keeper is movable and the arms of the clasp member being provided with detents for limiting the movement of the keeper in a direction away from said ledge element to confine said button between the ledge element and the keeper.

In testimony that I claim the foregoing I hereunto affix my signature.

GEORGE HAKE.
